N° 1,037

Design for Plates of a Box Stove
by N. S. Wedder, of Troy, N. Y.,
and Ezra Ripley of the same place,
Assignors to the said N. S. Wedder.

Patented Aug. 10. 1858.

File 1037

N. S. Wedder & Ezra Ripley, of Troy, N. Y.
Assignors to

N. S. Wedder, of Troy, aforesaid.
Letters Patent No. 1037 dated Aug. 10, 1858.

The schedule referred to in these Letters Patent and making part of the same.

To all whom it may concern:

Be it known that we, N. S. Wedder and Ezra Ripley, each of the City of Troy, in the County of Rensselaer, and State of New York, have jointly invented or produced a new and original ornamental Design

for Plates of a Box Stove; and we do hereby declare that the following is a full and exact description of the same, reference being had to the annexed photographic drawing making a part of this Specification.

Our Ornamental design for box-stove plates consists of the shield a, tomahawk b, ensigns c, cannon d, and cannon-balls e, drums f, rifles or muskets g, swords h, and other implements of war, formed and arranged together upon the scale-covered surface i, of the side-plate, A, of the Stove, and the particular scroll-leaf compound ornament j, formed and disposed upon the slot-covered surface k, of the front door, B, of the stove, substantially as shown in the annexed photograph.

What we claim as our joint invention or production and desire to secure by Letters Patent is the ornamental design of the plates of a box or six-plate stove, as herein described and represented in the annexed photographic drawing.
